(57) **CLAIM**

The ornamental design for a display package, as shown and described.

DESCRIPTION

FIG. 1 is a front, top and right side perspective view of a display package showing my new design;

FIG. 2 is a front elevational view thereof, the rear elevational view being a mirror image;

FIG. 3 is a left side elevational view thereof;

FIG. 4 is a right side elevational view thereof;

FIG. 5 is a top plan view thereof; and,

FIG. 6 is a bottom plan view thereof.

The broken line showings in FIGS. 1–6 are for illustrative purposes only and form no part of the claimed design.
